ATTORNEY

UNITED STATES PATENT OFFICE.

GEORGE S. BEST, OF SAN DIEGO, CALIFORNIA.

DESIGN FOR A DOOR SIGNAL.

Application filed November 4, 1925. Serial No. 15,339. Term of patent 3½ years.

To all whom it may concern:

Be it known that I, GEORGE S. BEST, a citizen of the United States, residing at San Diego, in the county of San Diego and State of California, have invented a new, original, and ornamental Design for a Door Signal, of which the following is a specification, reference being had to the accompanying drawings forming a part thereof.

The figure is a perspective view of my door signal by solid lines and showing by dotted lines the door jamb.

I claim:

The ornamental design for a door signal as shown.

In testimony whereof, I have hereunto set my hand at San Diego, California, this 27th day of October, 1925.

GEORGE S. BEST.
